UNITED STATES PATENT OFFICE.

GEORGE F. MAYER, OF CHICAGO, ILLINOIS.

PERMUTATION PADLOCK.

Application filed February 14, 1927. Serial No. 167,885.

My invention relates to permutation padlocks and has particular reference to a padlock which is easily operable and in which ready access is had to the tumblers so that the combination of the padlock can be very easily and quickly changed.

Another and further object of my invention is the provision of a padlock having a plurality of locking tumblers therein which, when placed in one position, perform the function of locking tumblers and when in reversed position are free of the locking bolt and do not perform a locking function when the padlock is suspended from the bow, thus enabling the omission of a good number of these locking tumblers and making the unlocking of the padlock a more simple operation than might be possible otherwise.

Another and further object of my invention is the provision of a padlock having a plurality of locking tumblers therein which is adapted to remain securely locked and which is not easily picked or unlocked, thus securing a larger measure of safety than what has been possible with locks of this character heretofore.

Another and further object of my invention is the provision of a padlock having the tumblers so arranged that when the lock is suspended from a staple the locking tumblers are in locked position and if reversed the locking tumblers are apt to slide into unlocked position but the free tumblers will thereupon slide into such position that the locking bolt is held in locked relation.

Another and further object of my invention is the provision of a padlock having a spring-pressed master tumbler therein and in which, in unlocking the device, it is necessary to operate the master tumbler last, thus releasing the locking bolt.

These and other objects of my invention will be more fully and better understood by reference to the accompanying drawings in which:—

Figure 1 is a side elevational view of my improved lock;

Figure 2 is an end elevational view of the lock shown in Figure 1;

Figure 3 is a side view of the casing with the cover plate removed;

Figure 4 is a cross sectional view of the lock on lines 4—4 of Figure 3;

Figure 5 is a cross sectional view through the lock casing on lines 5—5 of Figure 3;

Figure 6 is a detailed cross sectional view on lines 6—6 of Figure 3; and

Figure 7 is a side elevational view of the master tumbler.

Referring now specifically to the drawings and in which like reference characters refer to like parts throughout, a casing 10 is shown which is preferably cast integral with one open side and which is rectangular in shape, with a hollow space inside for receiving the various parts and mechanisms hereinafter described, and which has a side cover plate 11 secured thereto and held in position by means of the locking bolt, as will be more fully described hereinafter. A bow 12 is provided, the free ends of which extend into holes drilled into the casing 10 in a vertical direction and which is adapted to pass through a staple or other locking members when the device is in operation. A locking bar 13 is provided which is fitted into the casing 10 and extends transversely across the inside thereof and is held in position by a member 14 having its ends angularly turned and placed into frictional engagement with the sides of the locking bar 13, and with a pair of spacers 15 and 16 at the opposite sides of the locking bar 13, which are held to the casing in any suitable manner, as by screws or the like.

The locking bar 13 has an opening 17 extending longitudinally thereof within which a locking bolt 18 is positioned, the said locking bolt having a plurality of recesses 19, 19 in the upper face thereof which extend approximately one-half the distance across the said locking bolt 18 thereby providing a plurality of ribs 20, 20 on said locking bolt between the said recesses 19. The locking bar 13 has a plurality of slots 21, 21 formed therein, these slots extending downward through the bar 13 to the bottom of the recesses 19 formed in the locking bolt 18, thereby forming a plurality of spaced portions 22, 22 on the upper side of the locking bar 18. A plurality of sliding locking tumblers 23, 23 are provided which are rectangular in shape and have a pair of downwardly extending legs 24 and 25 on each side thereof adapted to extend downwardly on each side of the locking bar 13 and engage the said locking bar on each of its sides, the said legs being spaced a sufficient distance to allow for a sliding transverse movement of the tumblers 23 on the locking bar 13. Each of the tumblers 23 is recessed

at 26, this recess conforming in contour to ribs 20, 20 on the locking bolt 18 and when positioned free of the said ribs they permit a longitudinal movement of the locking bolt 18.

5 Positioned in the lower part of the casing 10 through openings formed in the lower wall thereof, is a plurality of studs 27, 27, each of said studs having a spring 28 mounted therearound and a collar 29 placed thereon, the members 27 at their inner ends extending through openings formed in the plate 14 immediately opposite the tumblers 23 so that as force is applied to the outer ends of the members 27, the tumblers 23 are moved in one direction only by the operator of the lock. The recess 26 in the tumblers 23 is cut at one side of the tumblers 23, that is, the distance from the edge of the recess to the leg 25 is less than the distance from the opposite side of the recess to the leg 24. When the tumblers 23 are placed in the lock as shown in Figure 4, and the leg 24 is abutting against the locking bar 13, the tumblers are in locked position, that is, the edge of the tumblers extends into the recesses 19 formed in the locking bolt 18 and between the ribs 20, 20, thus preventing longitudinal movement of the said locking bolt. When the tumblers 23 are reversed 30 so that the leg 25 is abutting against the upper side of the member 13, the recess 23 is in register with the locking bolt 18 so that the locking bolt 18 is free to move longitudinally. The short side of the tumblers 23 is indicated by being marked in some manner, as shown on the drawings which are lined to indicate the color black, so that in setting the combination for these tumblers if it is desired to utilize certain tumblers or arrange certain 35 combinations, the end of the tumblers which is marked in black is positioned adjacent the operating studs 27 and when it is desired to release the locking bolt 18, it is necessary only to release these tumblers by pushing inward on the operating members 27 with a nail, pencil, or any other operating means which will fit into the casing against the ends of the operating members 27, the casing in the meantime being held in a horizontal position 40 so the tumblers so moved will not slide back into their original positions, or the other tumblers slide towards the bow side of the lock casing. The lower side of the lock casing has a plurality of holes 30, 30 there- 45 through, each one of these holes having a numeral adjacent thereto which form indicating means for the operating plungers 27, the ends of the plungers projecting into the holes 30 as shown. As shown in the drawing, 50 the combination for operating the lock is set at 1, 3, 5, 7 and 9 and it will be noted that the black ends of the tumblers are opposite these openings.

60 The locking bolt 18 has a head 31 on the outer end thereof and sets in a recess 32 formed

on the outer side of the casing within which a spring 33 is mounted, one end of which abuts against the head 31 on the locking bolt 18 and the opposite end engages against the casing, the locking bolt passing through an opening 70 34 formed in the wall of the casing at one side thereof and through an opening 35 at the opposite side of the casing. The locking bolt 18 at the inner end thereof is slotted at 36 and engages a pin 37 passing through the casing 10 and through the slotted end of the locking bolt 18 to prevent the rotation of the locking bolt. The locking bolt adjacent the lower side of the casing has a pair of recesses 38 and 39 formed therein for the purpose of allowing a pair of studs 40 and 41 which are secured to the cover plate 11 to be inserted downwardly through holes formed in the locking member 13, these studs 40 and 41 having recesses in the sides thereof (Fig. 80 36), within which the locking bolt 18 is received as will be more fully described herein-after, the studs 40 and 41 fitting into recesses in the locking bolt 18 for the purpose of holding the cover plate 11 in position. A pin 42 85 is inserted through the locking member 13 and serves to cooperate with the recess 43 formed in one side of the locking bolt 18, by means of which the distance of longitudinal travel of the locking bolt 18 is controlled. 90

95 The bow 12 of the padlock is formed in the usual manner of bows of this character, one end of the bow being longer than the other, the ends of the bow being received in vertical openings 44 and 45 formed in the lock casing. The bow at one end thereof is recessed at 46 having a flat portion formed thereby with a head 47 being formed thereon and which is normally adapted to engage the free end of the locking bolt 18 when the padlock is in locked position. A recess 48 is formed in the side of the bow 12 which communicates with the recess 46 on one side thereof and which receives a pin 49 inserted 100 through the lock casing and prevents the complete withdrawal of the bow 12 from the lock casing 10, the pin 49 being loosely positioned in the casing and adapted to be removed therefrom when the cover plate 11 is removed from the casing 10, the pin 49 being received 105 into the recess 48 when the bow is in its farthest outward position as the bow is rotated to allow for easy fastening of the bow in a staple or the like. 110

115 A master tumbler 50 is illustrated in Figure 7 and shown in position also in Figure 3, this tumbler being formed in the same manner except that it is made longer on one side and adapted to cooperate with a transversely extending flat spring 51 positioned in the members 15 and 16 and extending transversely across the lock casing, this spring being spaced far enough from the other tumblers not to interfere with their operation and is adapted to hold the master tumbler 50 in con- 120

125

130

stant locked relation until relieved from this position by pressure on the operating member 27 opposite this tumbler. The spring 33 is normally compressed when the tumbler is in locked position and during the unlocking operation the locking tumblers are all placed in unlocked position and the master tumbler 50 operated as the last tumbler in the unlocking operation, so that when it is pushed upward to unlocked position the spring 33 expanding, forces the locking bolt outward to the limit of its travel as defined by the length of the recess 43, it being necessary to hold the master tumbler in unlocked position during this operation, whereas by placing the casing 10 in a horizontal position all of the other tumblers may be placed in unlocked position merely by pushing them into this position where they will remain.

In operation the device is quite simple in that the tumblers, if arranged in the form shown in the drawing and it is desired to place the padlock in locked position, the bow 12 is inserted through the staple or other locking member and is turned so one end thereof is inserted into the opening 44 and the bow pushed into the padlock casing as far as possible. The operator thereupon presses inwardly against the head of the locking bolt 18 pushing it inward so the inner end thereof extends over the shoulder 47 formed on the bow 12, the padlock is placed in vertical position whereupon the locking tumblers will drop into the position shown in Figure 4, thus preventing the withdrawal of the locking bolt 18 and holding the padlock in locked relation.

When it is desired to unlock the device if the master tumbler is not used, the padlock is placed in a horizontal position and the locking tumblers are pushed across the locking bolt by means of the operating members 27 and as soon as they are all in this position the spring 33 throws the locking bolt outward so the inner end thereof is beyond the head 47 allowing the bow to be withdrawn so that the opposite end of the bow is clear of the lock casing, allowing it to be removed from the staple or hasp, and the device unlocked. When in unlocked position the locking bolt 18 may be pushed far into the casing so the recesses 38 and 39 are in register with the studs 40 and 41, the inner end of the locking bolt 18 passing underneath the head 47 on the bow 12. When in this position the cover 11 can be easily removed by being lifted from the casing 10 and access had to the inside of the lock where the tumblers may be changed in any manner desired so that the combination of the operating tumblers may be changed by merely reversing the position of the locking tumblers 23, it only being necessary to bear in mind that the locking tumblers having the marked sides should be adjacent the operating members 27.

Should it be desired for any reason to dis-

assemble the entire lock when the cover plate 11 is removed the pin 42 can be removed, thus removing the locking bolt 18 and the pin 49 can also be removed so that the bow 12 can be easily taken from the casing 10. In re-assembling the device the bow is placed in position, the pin 49 dropped into place so the bow is held in proper position and after the locking bolt 18 is inserted in the lock member, the pin 42 is thereupon placed in position and pushed into the casing a sufficient distance so the recesses 38 and 39 are in alignment with the pin openings through the locking member 13, whereupon the cover plate 11 is placed into position and the locking bolt 18 allowed to return to its normal unlocked position in which position the locking bolt engages in the recesses formed in the sides of the pins 40 and 41, thus holding the cover plate 11 firmly in position and preventing the removal of this plate for the purpose of tampering with the lock. It will be understood that when the bow is in locked position the inner end of the locking bolt 18 abutting against the side of the bow adjacent the recess 46 prevents the locking bolt 18 being pushed in far enough for the removal of the plate 11 and that this plate can only be removed when the lock is in unlocked position.

If it is desired to use the master tumbler illustrated in Figure 5, this tumbler is inserted in the place of any one of the tumblers 23 that may be desired, and its position borne in mind by the operator of the lock so that when it is desired to unlock the device this tumbler is operated as the last one in the series, whereupon the locking bolt 18 will be thrown into unlocked position by the spring 33.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A permutation padlock comprising in combination, a casing, a bow, a locking member having a longitudinal opening therein, a locking bolt mounted in the opening in said locking member, and a plurality of sliding locking tumblers mounted upon said locking member adapted to engage the locking bolt when in locked position, said locking tumblers having recesses on their under sides adapted when in unlocked position to register with the longitudinal opening in said locking member and out of engagement with the locking bolt.

2. A permutation padlock comprising in combination, a casing, a bow, a locking member, said locking member having a longitudinal opening therein and a plurality of spaced

ribs thereon, a locking bolt having a plurality of ribs thereon, and a plurality of tumblers mounted between the ribs on said locking member and adapted to engage the locking bolt when in locked position, and having downwardly extending portions alongside of said locking member but spaced therefrom, whereby the said locking tumblers are slidably positioned upon said locking member.

3. A permutation padlock comprising in combination, a casing, a bow, a locking member having a longitudinal opening therein and a plurality of spaced ribs thereon, a locking bolt slidably mounted in the opening in said locking member having a plurality of ribs thereon, a plurality of transversely extending slidably mounted locking tumblers in said locking member having recesses in their under sides thereof adapted to register with the openings in the locking bolt when in unlocked position and out of register therewith when in locked position and in engagement with the said locking bolt.

4. A permutation padlock comprising in combination, a casing, a bow, a locking member in said casing having a longitudinal opening therein, and a plurality of ribs formed thereon, the said ribs extending approximately one-half the depth of the said locking member, a locking bolt slidably mounted in the longitudinal opening in said locking member having a plurality of ribs on one side thereof, and a plurality of reversible locking tumblers having recesses in their lower sides at one side of the centers thereof adapted to register with the opening in the said locking member when in one position on said locking bolt and out of register therewith when in reverse position and in engagement with the locking bolt when in locked position.

5. A permutation padlock comprising in combination, a casing, a bow, a removable cover for said casing, a locking member, a locking bolt, a plurality of slideable locking tumblers, a removable cover plate in said casing normally held in position by the locking bolt, and a pair of studs on said cover plate having recesses in the sides thereof within which the said locking bolt is adapted to fit.

6. A permutation padlock comprising in combination, a casing, a bow, a locking member having an opening therein and a plurality of ribs thereon, a locking bolt positioned in the opening in said locking member and having a plurality of ribs thereon whereby channels are formed in said locking member and said locking bolt, a plurality of sliding locking tumblers in said channels having means thereon to engage the ribs in the locking bolt when in locked position, a master tumbler, and means tending to hold said master tumbler in locked position.

7. A permutation padlock comprising in combination, a casing, a bow, a locking member having an opening therein and a plurality of ribs thereon, a locking bolt positioned in the opening in said locking member and having a plurality of ribs thereon whereby channels are formed in said locking member and said locking bolt, a plurality of sliding locking tumblers in said channels having means thereon to engage the ribs in the locking bolt when in locked position, a master tumbler, and a spring exerting its force on said master tumbler tending to hold it in locked position.

Signed at Chicago, Illinois, this 15th day of January, 1927.

GEORGE F. MAYER.
